UNITED STATES PATENT OFFICE.

NUMA E. MORGAN, OF ATLANTA, GEORGIA.

SMOKING PIPE.

Application filed January 11, 1923. Serial No. 611,917.

To all whom it may concern:

Be it known that I, NUMA E. MORGAN, a citizen of the United States, residing at Atlanta, in the county of Fulton and State 5 of Georgia, have invented certain new and useful Improvements in Smoking Pipes, of which the following is a specification.

The primary object of my said invention is the provision of a smoking pipe, wherein 10 the smoke is effectively cooled before entrance into the mouth of the smoker, the same being also freed from nicotine and moisture.

A further object of the invention resides 15 in the provision of such an article that is extremely simple of construction, embodying comparatively few parts, and these so correlated as to produce a comparatively rigid and highly improved smoking pipe.

20 The nature and advantages of the invention will be better understood when the following detailed description is read in connection with the accompanying drawings, the invention residing in the construction, 25 combination, and arrangement of parts as claimed.

In the drawings forming part of this application, like numerals of reference indicate similar parts in the several views, and 30 wherein:

Figure 1 is a longitudinal cross sectional view of a pipe constructed in accordance with the present invention.

Figure 2 is a transverse cross sectional view upon the line 2—2 of Figure 1.

Figure 3 is an elevational view of one end of the pipe stem employed in conjunction with this invention.

Figure 4 is a similar view of the opposite 40 end of the pipe stem.

Figure 5 is a fragmentary cross sectional view of one end of a slightly modified form of the invention.

Figure 6 is a view similar to Figure 5 of 45 a still further modified form of the invention, and

Figure 7 is a longitudinal cross sectional view of a cigar or cigarette holder embodying the general purpose of a smoke cooling 50 means as applied to the pipe shown in the above mentioned figures.

Referring to the drawings, and particularly to Figures 1 to 4 inclusive, my pipe embodies the provision of a bowl A, stem 55 B and mouth piece C. The bowl A may be

of any design compatible with the present invention, the lower end being formed with an internally screw threaded cross bore 5 adapted for the reception of a hollow screw threaded pipe section 6, one end of this pipe section 6 is formed with a cap 7 that is internally screw threaded to receive one screw threaded end of the before mentioned pipe stem B. The opposite end of the pipe section 6 is internally screw threaded for the 60 reception of a screw threaded clean out plug 8, and the bowl A and pipe section 6 have alined openings 9 therein for permitting of the withdrawal of the smoke from the bowl A. 70

The opposite end of the pipe stem B is also screw threaded for receiving an internally screw threaded cap 10, which cap 10 is provided with a central opening for receiving a centrally formed plug 11 upon the 75 before mentioned mouth piece C.

The stem B is of cylindrical formation, and is centrally longitudinally bored, which bore is in alinement with the before mentioned pipe section 6, and as is clearly 80 shown, this cylindrical barrel B is provided with spaced longitudinally extending bores 12 adjacent bores being connected by cross channels 13, beneath the surface of the end of the cylindrical stem and at one end thereof. The bores 13 are also connected at their opposite ends by incut channels 14, it being of course understood that the channels 13 at one end of the cylindrical stem B establish communication between certain of the bores 90 and that the bores 14 at the opposite end of the stem connect certain other of the bores for purposes hereinafter to be described. 85

One of the stem bores as 12' is unconnected at one end with either of the adjacent bores, this bore 12' communicating with the central bore of the stem by an opening 15 more clearly shown in Figure 1. 95

The mouth piece C is formed with a central smoke passage 15, the inner end of which 100 terminates at the upper inner end of the before mentioned integral plug 11, and communicates with one of the bores of the cylindrical stem B by a downwardly extending channel 16, more clearly shown in Figures 105 and 3. At the opposite ends of the stem B and within the said caps 7 and 10 are leather or rubber washers 17, which effectively prevents discharge of the smoke from the bores but allows the same to pass from 110

bore to bore through the instrumentality of the incut channels 13 and 14. Within the central bore of the stem B, there is provided a mass of cotton 17, which effectively prevents the entrance of nicotine or pieces of the tobacco into the smoke channels of the stem, and in view of the above description, it will at once be apparent that the smoke before passing outwardly through the channel in the mouth piece C will circulate entirely around the stem B, thereby effectively cooling the smoke before entrance into the smoker's mouth. For cleaning purposes, the plug 8 may be removed, and in view of the simplicity of the parts of this pipe, the same may be readily disassembled whenever occasion demands.

In Figure 5, the bowl A is formed at its lower end with a wedge-shaped opening 5' for receiving the wedge shaped pipe section 6', which construction will facilitate the more ready removal and attachment of this pipe section, and in Figure 6, the bowl A'' is formed at its lower end with a wedge-shaped socket 5'' for receiving the wedge-shaped nipple or pipe section 6'', which has communication with the interior of the pipe bowl, through the instrumentality of a pendent slot 9' in the base of the bowl A'.

In Figure 7, I have shown a cigar or cigarette holder including the general features of construction attributed to my several forms of pipes, and in this instance, the holder includes a stem 18, which is of conical shape, and is formed with interconnected bores 19, for effecting a smoke channel within the stem for cooling the same, which formation of bores is substantially the same as those attributed to the cylindrical barrel B in the other figures. The large end of this stem 18 is screw threaded for receiving a screw threaded cap 20, which carries a leather or rubber washer 22 provided for effectively sealing the extreme ends of the bores. The opposite smaller end of this stem is also screw threaded for receiving an internally screw threaded cap 23, which carries a mouth piece 24. A mass of cotton or other smoke purifying substance 25 is also inserted within this conical stem, which is retained therein by a metal cap 26 formed with a central opening.

While I have herein shown and described the preferred embodiments of the present invention, it is nevertheless to be understood that minor changes may be made

therein, without departing from the spirit and scope of the invention as claimed.

What I claim as new is:

1. A smoking pipe including a stem formed with a central bore extending longitudinally throughout the stem, and a plurality of small bores extending longitudinally thru the stem and arranged in concentric relation with the central bore having communication therewith and with each other to provide a continuous passage through the central bore and to the radial bores and successively therethrough back to the central bore, the points of communication between the central bore and the concentric bores being spaced apart, a mouth piece for engagement with one end of the stem having a plug slidably fitting the central bore and formed with a passage to communicate with one of the passages from the central bore to the small concentric bores, and a bowl adapted for engagement over the other end of the stem having a passage communicating with the central bore of the stem formed to close the ends of the small longitudinal concentrically arranged bores except for inter-communication between said bores. 85

2. A smoking pipe including a stem formed with a central bore extending longitudinally throughout the stem, and a plurality of small bores extending longitudinally thru the stem and arranged in concentric relation with the central bore having communication therewith and with each other to provide a continuous passage through the central bore and to the radial bores and successively therethrough back to the central bore, the points of communication between the central bore and the concentric bores being spaced apart, a mouth piece for engagement with one end of the stem having a plug slidably fitting the central bore and formed with a passage to communicate with one of the passages from the central bore to the small concentric bores, a pipe section for engagement over the other end of the stem adapted to close the small concentric longitudinal bores at the end portion of the stem except for inter-communication therebetween and formed with a central bore communicating with the central bore of said stem, and a bowl mounted on said pipe section having an opening registering with an opening in said pipe section to provide communication of the bowl with the central bore. 110

In testimony whereof I affix my signature.
NUMA E. MORGAN.
